UNITED STATES PATENT OFFICE.

WILLIAM THOMAS COHOLAN, OF NEW BRITAIN, CONNECTICUT.

TRUSS.

1,279,657.

Specification of Letters Patent. Patented Sept. 24, 1918.

Application filed September 21, 1917. Serial No. 192,470.

To all whom it may concern:

Be it known that I, WILLIAM THOMAS COHOLAN, a citizen of the United States, residing at New Britain, in the county of 5 Hartford and State of Connecticut, have invented certain new and useful Improvements in Trusses, of which the following is a specification.

My invention relates to improvements in 10 trusses, and the object of my improvement is to produce a truss that is held in place by a belt, without the use of springs, the belt portion being made of fabric, suitable to be washed, that has few metal parts, such metal 15 parts as are provided being removable, and the belt construction is double, comprising an inner belt that supports the pad and an outer belt for applying pressure, and the pad is so related to the belt structure as to 20 be subject to a positive and substantially direct inward pressure.

In the accompanying drawing:—

Figure 1 is a plan view of a truss embodying my invention.

25 Fig. 2 is a similar view, on an enlarged scale of the front portion of the same.

Fig. 3 is a front elevation of the same.

Fig. 4 is a similar view of the inner belt portion.

30 Fig. 5 is a plan view, on a still further enlarged scale, of the pad and adjacent parts.

Fig. 6 is a sectional view on the line $\alpha\alpha$ of Fig. 3.

35 Fig. 7 is a plan view of the securing device for the inner belt.

My improved truss consists of a duplex belt construction, comprising an inner belt 10 and an outer belt 11 superimposed on the 40 said inner belt, and a pad 12 of special construction that is incorporated in the structure of the inner belt 10 and positioned at the proper point for applying pressure to the person as the particular case may require, such pressure when in use being applied through the medium of the outer belt 11.

Both belts are made preferably of woven 50 cotton fabric, suitable for being washed without injury, and they are held in coöperating position by means of a set of loops 26 secured to the inner belt 10 and projecting outwardly from the outer face thereof

suitably to have the outer belt 11 slipped therethrough.

The inner belt has the overlapping end portions secured together by a loop plate 13 that is relatively flat, so as to avoid excessive bunching of material at the point of connection for the said end portions, such connection being relied upon merely for the most part only for the purpose of holding the ends in their proper relative position, as the outer belt 11 is relied upon for the actual or positive holding effect.

For holding the ends of the outer belt 11 a tongueless buckle 14 is preferably used, such as shown or of any other suitable form.

The loop plate 13 is made of sheet material, and comprises a middle cross-bar 15 to which the fixed end 16 of the inner belt 10 is secured and a pair of end bars 17, the free end 18 of the said belt being rove through the openings between the bars.

In use the inner belt 10 is first brought 75 snugly to the position desired, with an appreciable amount of tension, and then the outer belt 11 is tightened to the necessary tension to produce the desired holding effect.

The pad 12 is made of special form as mentioned in order to localize the holding pressure, whereby a relatively small belt tension will suffice for effecting the necessary local, inward pressure. The particular construction of the pad for effecting this result comprises a part 24 that serves as the pad proper that projects inwardly from the inner face of the inner belt, 10, and a part 19 that projects outwardly an appreciable amount in the form of a pad extension on the outer face of the said inner belt 10.

Thus as the outer belt 11 is tightened the portion 20 that extends over the pad 12 is in 95 positive contact with the outer part or pad extension 19 and exerts a pressure that is directed generally inwardly, and independently of the adjacent body portion 21 of the structure of the inner belt 10.

The result described is facilitated by the use of a pair of slip loops 26, positioned one on each side of and adjacent the pad 12, as particularly shown in Fig. 5, the said slip loops 26 serving as guides for the outer belt 105 relatively to the said pad.

The tongueless buckle 14 is removably secured to the fixed end of the outer belt 10 in some suitable manner as by means of a loop 25 engaged with a bar 22 on the buckle 14, the overlapping ends of the loop 25 being secured together by means of a button 23 and button hole.

The fixed end portion 16 of the inner belt 10 is in the form of a loop that passes around the middle bar 15 of the loop plate, as shown in Fig. 2, and the free end portion 18 in its engagement with the loop plate passes through the two openings in the loop plate 13, one on each side of the said middle bar 15, and has a portion superimposed on the end loop portion 16 on the outer side thereof, and which in use is in contact with the outer belt 11 and pressed inwardly thereby, so as to produce a holding friction between the superimposed portions of the inner belt.

The use of the tongueless buckle 14 for the outer belt permits of tightening the belt positively to correspond to the particular adjustment of the effective length of the inner belt 10.

I claim as my invention:

1. A truss comprising an inner belt for supporting the pad, and an outer belt for applying pressure to the said pad, the pad

being secured to the said inner belt, and the said outer belt being superimposed on the said inner belt and comprising a portion that passes over the said pad and each of the said belts comprising a complete belt structure, with overlapping ends, and having means for securing together the mating ends of each individual belt.

2. A truss comprising an inner belt for supporting the pad, and an outer belt slidably mounted on the said inner belt for applying pressure to the said pad, the pad being secured to the said inner belt, and the said outer belt being superimposed on the said inner belt and comprising a locally curved portion that passes over the said pad, the said pad comprising a part that projects inwardly from the said inner belt and a pad extension on the outer side of the said inner belt that is in contact with the said locally curved portion of the outer belt and a pair of slip loops being mounted on the said inner belt and positioned one on each side of and adjacent to the said pad, suitably to serve as guides for the outer belt relatively to the said pad.

WILLIAM THOMAS COHOLAN.
